(57) **CLAIM**

I claim the ornamental design for a class ring wrap, as shown and described.

DESCRIPTION

FIG. 1 is a top and left side perspective view of a class ring wrap showing my new design;

FIG. 2 is a left side elevation view thereof, the right side elevational being identical;

FIG. 3 is a front elevational view thereof, the rear elevational view being identical;

FIG. 4 is a top plan view thereof; and,

FIG. 5 is a bottom plan view thereof.

The broken lines shown in the drawings illustrate portions of the class ring wrap and form no part of the claimed design.
